UNITED STATES PATENT OFFICE.

CHARLES W. MANLEY, OF NORTH ABINGTON, MASSACHUSETTS.

SCARF.

SPECIFICATION forming part of Letters Patent No. 276,845, dated May 1, 1883.

Application filed March 19, 1883. (No model.)

To all whom it may concern:

Be it known that I, C. W. MANLEY, of North Abington, in the county of Plymouth, of the Commonwealth of Massachusetts, have invented a new and useful Improvement in Bosom-Scarfs; and I do hereby declare the same to be described in the following specification and represented in the accompanying drawings, of which—

- 10 Figure 1 is a view of the body part or sections of one of my improved scarfs in an unfolded state. Fig. 2 is a front view, and Fig. 3 a rear view, of it as having its sections folded together.
- 15 The scarf-body is composed of the six sections A, B, C, D, E, and F, formed and arranged as represented, and connected so as to be capable of being folded relatively to each other in manner as hereinafter described, the 20 lower median section, E, being provided with a button-hole, *a*, arranged in it at its middle, as shown. These sections are to be covered on one side of the series with cloth of a like or different pattern or color from that used in 25 covering the opposite side. Each of the sections is trapezoidal in form, as shown, and each of the two median ones has its ends at acute angles to its longer side, the next adjacent ends of the other sections being formed 30 in like manner. In folding the sections the three, A B C, connected are to be folded down, so as to lap upon either side of the combined

sections D, E, and F. Next the pair of sections A and D, folded together, and the pair of sections C and F, folded together, are to be 35 folded obliquely across each other and the folded median sections, B and E, so as to leave the larger median section, E, in rear of and to have its button-hole covered by the lesser median section, B. In this way the 40 scarf may be folded either side out and have its button-hole covered in front by the smaller median section. The several sections constituting the scarf or scarf-body may be in one piece, of pasteboard, or other proper material, 45 creased or bent so as to fold, in manner as above described, on the lines *b c*, *d e*, *e f*, *g h*, and *h i*, as shown in Fig. 1, such piece being suitably 50 covered with cloth; or the sections may be in separate pieces suitably covered and connected, so as to fold in manner substantially as specified.

I claim—

The double-folding bosom-scarf, substantially as described, composed of the trapezoidal sections A B C and D E F, constructed and adapted to fold together, and a button-hole in the larger median section, essentially as set forth.

CHARLES WILLIAM MANLEY.
